Primary Examiner—Celia Murphy*Attorney, Agent, or Firm*—Richard C. Litman[57] **CLAIM**

The ornamental design for a jacket having a decoration accessory, as shown and described.

DESCRIPTION

FIG. 1 is a rear environmental perspective view of a jacket having a decoration accessory, showing my new design;

FIG. 2 is a front elevational view thereof;

FIG. 3 is a left side elevational view thereof, the right side being a mirror image;

FIG. 4 is a rear elevational view thereof;

FIG. 5 is a rear elevational view thereof, with the accessory in an optional folded or stowed condition;

FIG. 6 is a top view of the jacket, again with the accessory displayed or erected; and,

FIG. 7 is a bottom view thereof, with the accessory displayed.

The broken line showing of a person in FIG. 1 is for illustrative purposes only and forms no part of the claimed design. The broken lines on the rear of the jacket in FIGS. 1, 3, and 4 and on the front of the jacket in FIGS. 2, 6, and 7 represent conventional stitching.
